UNITED STATES PATENT OFFICE.

HARRY C. STICKEL, OF STAR JUNCTION, PENNSYLVANIA.

TRACK-FASTENING.

No. 810,027.

Specification of Letters Patent: Patented Jan. 19, 1909.

Application filed June 3, 1907. Serial No. 376,956.

To all whom it may concern:

Be it known that I, HARRY C. STICKEL, a citizen of the United States, residing at Star Junction, in the county of Fayette and State of Pennsylvania, have invented a new and useful Track-Fastening, of which the following is a specification.

The invention relates to improvements in track fastenings.

10 The object of the present invention is to improve the construction of metallic cross ties, and to provide a simple and comparatively inexpensive metallic cross tie, having means for fastening the various rails, employed in track construction, without the use of spikes, or similar fastening devices, and capable of dispensing with the bolts usually employed in rail joints.

20 A further object of the invention is to provide a metallic cross tie of this character, adapted to firmly grip the ballast, whereby the cross tie will be prevented from slipping either longitudinally or transversely.

With these and other objects in view, the 25 invention consists in the construction and novel combination of parts hereinafter fully described, illustrated in the accompanying drawings, and pointed out in the claims hereto appended; it being understood that 30 various changes in the form, proportion, size and minor details of construction, within the scope of the claims, may be resorted to without departing from the spirit or sacrificing any of the advantages of the invention.

In the drawings:—Figure 1 is a plan view of a portion of a track provided with metallic cross ties, constructed in accordance with this invention. Fig. 2 is a horizontal sectional view of a portion of the track, illustrating the arrangement of the parts and a rail joint. Fig. 3 is a sectional view, taken substantially on the line 3—3 of Fig. 2. Fig. 4 is a sectional view, taken 40 longitudinally of a cross tie on the line 4—4 of Fig. 3. Fig. 5 is a detail view of a portion of the cross tie, illustrating the manner of removing the rails. Fig. 6 is a reverse plan view of the cross tie shown in Fig. 4. Fig. 7 is a sectional view on the line 7—7 of Fig. 1, and illustrating the construction for securing the main rails, the side track rails and the guard rails to the cross tie. Fig. 8 is a detail sectional view, taken substantially 50 on the line 8—8 of Fig. 7. Fig. 9 is a detail perspective view of one of the side wedges.

Fig. 10 is a similar view of one of the intermediate wedges. Fig. 11 is a detail perspective view of the interlocking fish plates, the parts being separate.

60

Like numerals of reference designate corresponding parts in all the figures of the drawings.

The metallic cross tie 10, illustrated in detail in Figs. 4 to 6 inclusive of the drawings, consists of a horizontal base portion 11, a central vertical longitudinal web or connecting portion 12, and a top portion 13. The longitudinal recesses 14, formed at the sides of the metallic cross tie by the top and bottom portions and the central connecting web, are designed to be filled with the ballast of a road bed to assist in anchoring the metallic cross tie, and the base portion is provided at its lower face with recesses 15, and it has side notches 16 to receive the ballast, whereby the cross tie is prevented from slipping either longitudinally or transversely. The bottom recesses 15, which are spaced apart, have top, side and end walls, 70 and the side notches are triangular and form inwardly converging side edges. Each of the metallic cross ties employed, is constructed in this manner, and they differ only in the track clamping means, a single side 75 wedge 17 being employed for clamping a single rail and a similar side wedge and an intermediate wedge 18 being used where two adjacent rails, such as a main rail, and a 80 guard rail, or a main rail and a side rail, or two converging rails of a switch are to 85 be clamped to a cross tie.

The tie 10 is provided at each end with spaced integral wedge-engaging and rail-engaging jaws 19 and 20, and it has a horizontal 90 rail seat 21, located adjacent to the rail-engaging jaw 20 and adapted to receive a rail 22. The cross tie is also provided with a recess 23, located adjacent to the wedge-engaging jaw 19 and extending below the 100 plane of the rail seat 21 to receive the bottom portion of the side wedge 17. The side wedge 17 consists of a body portion, provided at the bottom with a flange 24, which is tapered longitudinally of the body portion, whereby when the side wedge is driven between the jaw 19 and the rail 22, the latter will be firmly clamped against the jaw 20, and will be securely held in an upright position and effectually prevented from accidentally spreading or twisting. The flange 105 extends into the tapering space beneath the 110

jaw 19, which is set at an inclination. The space between the rail seat 21 and the jaw 20 conforms to the configuration of the adjacent bottom portion of the rail, as clearly illustrated in Fig. 4. The wedge is provided at its rail-engaging face with a longitudinal groove or recess 23, which receives the bottom flange of the rail, whereby the wedge is adapted to abut against the web of the rail 10 and extend beneath the bottom flange of the same. The wedge is provided at the top with a longitudinal rib 26, located at and forming a continuation of the rail-engaging face, and abutting against and supporting 15 the head of the rail, and conforming to the configuration of the same. The side wedge is securely held in engagement with the rail by means of a vertically disposed set screw 27, mounted in a threaded perforation of the 20 wedge-engaging jaw 19 and engaging the upper face of the bottom flange 24. The set screw 27 is provided with a polygonal head, and is adapted to be turned by a wrench, or other suitable tool.

25 The wedge 17 is located at the inner side of one of the rails 22, and is arranged at the outer side of the other rail 22, so that when the wedges are removed, the cross tie may be shifted longitudinally to bring the space between the engaging portions of the jaws 19 and 20 directly above the bottom flanges of the rail, so that the latter may be easily removed, as illustrated in Fig. 5 of the drawings. The rails may be removed by lifting 35 them out of the spaces between the jaws 19 and 20; or the cross tie may be partially rotated to carry the jaws below the plane of the rails.

The track clamping means, shown in detail in Figs. 4 and 5, may also be employed in connection with a rail joint, consisting of fish plates 28 and 29, located between the jaws 20 and the wedge 17 and retained by the same in engagement with the rails. The 40 fish plate 28 is provided with transversely disposed studs 30, which extend through perforations 31 of the ends of the rails and engage registering perforations 32 of the fish plate 29. This construction will obviate the 45 necessity of employing both spikes and bolts for securing the ends of the rails to the cross ties, and it enables the ends of the rails to be arranged in the usual manner between two cross ties, as clearly illustrated in Figs. 2 and 3 of the drawings.

The manner of securing a pair of rails at each end and at an intermediate point of a cross tie, is illustrated in Fig. 7 of the drawings, where two guard rails 33 and 34 are 50 clamped adjacent to one of the main rails 22 and the outer siding rail 35, and the other main rail 22 and the inner rail 36 of the siding are clamped to the cross tie 10* at the center thereof. The three track fastenings, shown in Fig. 7, are correspondingly arranged to enable the cross tie to be shifted longitudinally to permit the removal of the rails. The central and left hand track fastenings each embodies a rail-engaging jaw 37 and a wedge-engaging jaw 38 and are 70 constructed exactly alike, while the right hand track fastening is of a slightly different construction. The cross tie is provided adjacent to the rail-engaging jaw with a rail seat 39, and it has a recess 40, extending from the jaw 38 to a point near the center of the bottom of the adjacent rail. A side wedge 41, similar to the side wedge heretofore described, is interposed between the jaw 38 and the adjacent rail, and is retained in engagement with the rail by a set screw 42. The cross tie is also provided with a recess 43, extending from the rail-engaging seat 39 and terminating short of the recess 40 to provide a transverse rib 44, 80 which is located centrally of the bottom of the rail, which is engaged by the side wedge. The intermediate wedge 18, which is seated in the recess 43, is interposed between the adjacent rails and is provided at its engaging side faces with longitudinal grooves or recesses 46 to receive the bottom flanges of the rails, and it is provided at opposite sides of its upper face with ribs 47, which abut against and support the heads of the 95 rails. The small end of the wedge is provided with perforations 48, adapted to receive a split key 49, which is spread to retain it in one of the perforations 48 and which is adapted to engage one side of the cross 100 tie, whereby the intermediate wedge is held against longitudinal movement. The rib 44, is arranged centrally of the rail, which is engaged by the side wedge 41, and it forms a firm support for such rail and relieves the 105 recessed portions of the side and intermediate wedges. The right hand track fastening, shown in Fig. 7, embraces spaced wedge-engaging jaws 37* and 38. The cross tie has side recesses 40 and 49* and an intermediate recess 43, and these recesses form transverse ribs 44 and 44*, which are located centrally of the bottoms of the rails 34 and 35. Side wedges 41 and 41* are employed, and the side wedge 41 is interposed 110 between the jaw 38 and the adjacent rail, and is retained in engagement with the rail by a set screw 42. The other side wedge 41* is interposed between the jaw 37* and the rail 34, and is retained in engagement with the 115 said rail 34 by a set screw 42*. An intermediate wedge 18, which is seated in the central recess 43, is interposed between the rails 34 and 35. This wedge, which is constructed in the same manner as the other 120 intermediate wedge, is held against longitudinal movement by a key 49. In each instance, the wedge-engaging jaw 38 is arranged at the left hand end of the track fastening means in Fig. 7 of the drawings, 130

so that the cross tie is adapted to be moved longitudinally to arrange the spaces between the jaws 37 and 38 directly below the bottom flanges of the rails to permit the latter to be either lifted out of the space between the jaws, or the cross tie to be rotated to carry the jaws below the plane of the rails.

The single rail-clamping means and the double rail-clamping means will, as clearly indicated in Fig. 1 of the drawings, enable all of the rails of a track equipment to be secured to the cross ties without the use of spikes, and the wedges may be made of various sizes to suit the space between the rails.

Having thus fully described my invention, what I claim as new and desire to secure by Letters Patent, is:—

1. The combination of a cross tie provided at its upper face with upwardly projecting spaced rail and wedge-engaging jaws and having a rail seat arranged adjacent to the rail-engaging jaw, said cross tie being also provided between the jaws with a recess located adjacent to the wedge-engaging jaw, a side wedge fitting in the recess and provided with a groove to receive the bottom flange of a rail, and means piercing the wedge-engaging jaw for retaining the wedge in engagement with the rail.

2. The combination of a cross tie provided with spaced rail and wedge engaging jaws projecting from the upper face to the cross tie, a side wedge seated on the cross tie and having its upper portion engaged by the adjacent jaw, and a screw piercing the wedge engaging jaw and engaging the wedge to retain the latter in place.

3. The combination of a cross tie provided at its upper face with spaced rail and wedge-engaging jaws and having a rail seat arranged adjacent to the rail-engaging jaw, said cross tie being also provided between the jaws with a recess located adjacent to the wedge-engaging jaw, a side wedge fitting in the recess and provided at one side with a groove to receive the bottom flange of the rail and having a tapering flange at the opposite side, which extends beneath the wedge-engaging jaw, and a screw piercing the wedge engaging jaw and engaging the wedge.

4. The combination with a pair of adjacent rails, of a cross tie having spaced integral rail and wedge-engaging jaws projecting from the upper face of the cross tie, the rail-engaging jaw being in engagement with one of the rails, a side wedge interposed between the other jaw and the other rail, and an intermediate wedge interposed between and interlocked with the rails.

5. The combination with two adjacent rails, of a cross tie provided at its upper face with upwardly projecting rail and

wedge-engaging jaws and having a rail seat 65 adjacent to the rail-engaging jaw receiving one of the rails, a side wedge interposed between the other rail and the wedge-engaging jaw, and an intermediate wedge seated on the bottom of the recess and interposed between the rails and provided at opposite sides with grooves to receive the bottom flanges of the rails, whereby it is interlocked with the latter.

6. The combination with two adjacent 75 rails, of a cross tie provided at its upper face with upwardly projecting rail and wedge-engaging jaws and having a rail seat adjacent to the rail-engaging jaw receiving one of the rails, a side wedge interposed between the other rail and the wedge-engaging jaw, and an intermediate wedge seated upon the bottom of the recess and interposed between the rails and provided at 80 opposite sides with grooves to receive the bottom flanges of the rails and having ribs at its upper face to engage under the heads of the rails.

7. The combination with two rails, of a cross tie having upwardly projecting rail 90 and wedge-engaging jaws at its upper face and provided adjacent to the rail-engaging jaw with a seat to receive the other rail and having recesses located between the seat and the wedge-engaging jaw, said cross tie being provided between the recesses with a projecting rib to receive the other rail, a side wedge arranged in and seated upon the bottom of one of the recesses of the cross tie and interposed between the latter rail and 100 the wedge-engaging jaw and provided with a groove for the bottom flange of such rail, and an intermediate wedge seated in the other recess upon the bottom thereof and provided at opposite sides with grooves to 105 receive the bottom flanges of the rails.

8. The combination with two rails, of a cross tie provided with spaced jaws projecting upwardly from the upper face of the said tie, a side wedge interposed between one 110 of the jaws and the adjacent rail, and an intermediate wedge seated upon the tie interposed between, engaging and interlocked with the rails.

9. The combination with two rails, of a cross tie having spaced jaws projecting upwardly from the upper face of the cross tie, intermediate and side wedges interlocked with the rails, and means for retaining the wedges seated upon the tie between the jaws 120 and in engagement with the rails.

In testimony, that I claim the foregoing as my own, I have hereto affixed my signature in the presence of two witnesses.

HARRY C. STICKEL.
